Primary Examiner — Lucy Lieberman*(74) Attorney, Agent, or Firm* — Brooks Kushman P.C.**CLAIM**

The ornamental design for a watch, as shown and described.

DESCRIPTION

FIG. 1 is a front elevation of a watch showing our new design; FIG. 2 is a perspective view of the watch case of FIG. 1; FIG. 3 is a side view of the watch case of FIG. 1; FIG. 4 is another side view of the watch case of FIG. 1; and, FIG. 5 is a rear view of the watch case of FIG. 1.

The writing on the dial that is shown in broken lines in FIG. 1 does not form part of the claimed design. The other broken lines in the drawings are used to show portions of the watch and band that do not form part of the claimed design.
